UNITED STATES PATENT OFFICE.

WILLIAM H. RUNGE, OF SENECA FALLS, NEW YORK, ASSIGNOR TO THE SENECA FALLS MANUFACTURING CO., INC., OF SENECA FALLS, NEW YORK.

RELIEVING ATTACHMENT FOR LATHES AND THE LIKE.

1,339,983.

Specification of Letters Patent.

Patented May 11, 1920.

Application filed March 3, 1919. Serial No. 280,323.

To all whom it may concern:

Be it known that I, WILLIAM H. RUNGE, a citizen of the United States, residing at Seneca Falls, in the county of Seneca and State of New York, have invented a new and useful Improvement in Relieving Attachments for Lathes and the like, of which the following is a specification.

This invention relates to relieving attachments for lathes or analogous machines, and more particularly to attachments of this kind in which the extent of the backing off movement may be varied.

The objects of the invention are to provide an attachment of this kind of improved and simplified construction; also to provide a mechanism of this kind in which adjustments for varying the backing off movement can be readily effected; also to provide a mechanism of this kind in which the relieving attachment may be readily rendered inoperative so that the lathe may be used in the usual manner; also to provide means of improved construction for placing the tool in different angular positions relatively to the work; also to improve the construction of apparatus of this kind in other respects hereinafter specified.

In the accompanying drawings:

Figure 1 is a top plan view of a relieving attachment embodying the invention.

Fig. 2 is an end elevation thereof.

Fig. 3 is a fragmentary sectional elevation thereof on line 3—3, Fig. 1.

Fig. 4 is a fragmentary sectional elevation thereof also on line 3—3, Fig. 1, showing some of the parts in different positions.

Fig. 5 is a side elevation thereof, partly in section.

Fig. 6 is a longitudinal sectional elevation thereof on line 6—6, Fig. 1.

Fig. 7 is a view showing some of the movable members of the relieving attachment removed from the housing.

Figs. 8 and 9 are transverse sectional elevations thereof on lines 8—8 and 9—9, respectively, Fig. 6.

A represents the usual tool carriage movable lengthwise of the lathe in any suitable manner and having a carriage cross slide A' slidable transversely thereon. A² represents a tool slide base which is adapted to be secured in various angular positions with regard to the carriage cross slide A', and A³ represents a tool slide which is movable

relatively to the tool slide base. The tool slide A³ includes the usual post or holder B for the tool b and may be of any usual or suitable construction. The tool slide A³ has a limited movement relatively to the tool slide base A², depending upon the amount of backing off or relieving to be effected by the tool, the tool slide being guided in its movements by the usual slot in the tool slide base, in which a part a of the tool slide engages. The tool slide is drawn away from the work by means of a spring a' or other suitable means, the tension of the spring being preferably adjusted by means of a threaded bolt a² or the like. All of these parts may be of any usual or suitable construction and of themselves constitute no part of this invention.

The movement of the tool toward the work against the action of the spring a' for the purpose of backing off or relieving the teeth of cutters or the like may be effected by any suitable means, a rotary shaft C being preferably employed which is driven by means of suitable gearing (not shown) at the head end of the lathe, the shaft being driven at a definite ratio with regard to the work. The shaft C is suitably connected to a cam shaft C' which is journaled in a housing member D secured to or formed integral with the tool slide base A². The shaft C' is provided with a cam E by means of which the backing off movement of the tool is effected and which may be of any suitable construction, the cam shown being provided with two cam faces so that one revolution of the cam shaft C' causes two movements of the tool toward the work, the tool being withdrawn by means of the spring a'. A cam of any other form may be employed if desired.

The cam E, in the construction shown, acts upon the tool slide A³ through the medium of a pin F, suitably secured on the tool slide A³ and extending into operative relation to the cam and through the medium of a cam lever G which is interposed between the cam and the pin F and by means of which the extent of movement imparted by the cam to the tool slide is varied. This lever is provided with a projecting portion g, Figs. 6 and 7, which engages the face of the cam, a body portion arranged beyond the end of the cam and provided with a slot or groove g' in which the pin F of the tool

slide engages, and a stud g^2 projecting from the body portion of the lever G and entering a hole or bearing formed in an adjusting head, knob or member H, which is rotatably mounted in the end of the housing D. The adjusting head H is also provided with a post or pin h to which a spring h' is attached, the other end of the spring being secured to the cam lever G at a distance 10 from the stud g^2 thereof and is adapted to hold the projection g of the cam lever in engagement with the face of the cam E. The rotation of the cam E causes the projecting portion g of the cam lever to move 15 in accordance with the throw of the cam, and swings the lever G about the axis of the stud g^2 . In order to vary the movement of the tool slide A³, the adjusting head H is turned so as to move the stud g^2 toward or 20 from the pin F and thereby change the amount of movement imparted to the pin F by the cam lever. When the cam lever is in the position shown in Fig. 3, the pin F receives nearly its maximum movement, being 25 in proximity to the outer end of the cam lever G, which end is subjected to the full throw of the cam. When the adjusting head H is turned so as to bring the stud g^2 of the cam lever G opposite to the pin F, 30 no movement is imparted to the pin F since this portion of the cam lever is pivoted in the head H and therefore receives no movement from the cam tending to move the pin F. By adjusting the head H, the throw or 35 movement of the pin F and the tool slide connected thereto may be controlled as desired.

The adjusting head H is preferably held against endwise movement relatively to the 40 housing D by means of a pin or screw I, the end of which engages in a groove or slot i formed in the adjusting head H, thus preventing endwise movement of the head and also limiting the extent to which the head 45 may be turned about its axis for the purpose of placing the cam lever G in various positions. In order to secure the head H in any desired position, the end of the housing D in which the head is arranged is preferably split, and a screw or the like i' is provided which clamps the head in any desired 50 position relatively to the housing D. The outer periphery of the head H is preferably graduated as shown at i'' , the graduations 55 corresponding to the movement imparted to the tool slide A³ by the cam and cam lever.

By means of the mechanism described, a 60 compact and efficient relieving attachment is produced which is entirely inclosed in a housing or casing and which can be readily adjusted to effect any desired movement of the tool slide A³, by merely turning the adjusting head H and clamping the same in the desired position. The relieving attachment 65 has the further advantage that it can

be instantly placed out of commission by setting the head H to the zero position, in which position the cam lever G is placed as shown in Fig. 4, and in which position no movement is transmitted to the slide A³. 70

In order to place the tool in any desired angular position relatively to the work, the following means are preferably employed.

The carriage cross slide A' is provided with a post or pivot K journaled in the carriage cross slide and extending into a hole in the tool slide base A², thus permitting the tool slide base to be turned about the post K relatively to the carriage cross slide A'. Suitable means are preferably provided for 80 locking the tool slide base A² to the carriage cross slide in such a way as to hold these two parts in any desired angular relation to each other. For this purpose the post or pivot K is provided with a hole k through 85 which a pin L extends which has an eccentric portion l arranged within the hole k of the pin or post. The opposite ends of the pin are suitably journaled in the tool slide base A² and the pin is provided at its outer 90 end with a head l' by means of which the pin can be turned. The hole k of the post K is so placed relatively to holes in the tool slide base A² that by turning the pin, the eccentric portion l thereof presses against 95 the upper wall of the hole to press the post K upwardly, thereby drawing the tool slide base A² and the carriage cross slide securely together, and preventing relative movement of these parts. The eccentricity of the portion l of the pin is preferably made small so 100 that the pin locks itself. In this manner the tool slide base can be quickly locked or unlocked from the carriage cross slide and can be readily adjusted with regard to the 105 same.

I claim as my invention:

1. In a relieving mechanism, the combination with a movable tool-carrying member, a cam for causing said member to move 110 relatively to the work, a lever interposed between said cam and said tool-carrying member, and means for adjusting the position of said lever about the axis of said cam to vary the movement imparted to said 115 tool-carrying member.

2. In a relieving mechanism, the combination with a movable tool-carrying member, a cam for imparting movement to said member, a lever engaging at one end on said cam and pivoted at the other end thereof, means for holding said tool-carrying member in engagement with said lever, and means for moving said lever relatively to 120 said tool-carrying member to vary the extent of movement of said member.

3. In a relieving mechanism, the combination with a movable tool-carrying member, a cam for imparting movement to said member, a housing for said cam, a lever ar- 125

ranged in said housing beyond said cam and having a part engaging said cam and a pivoted part, means for holding said tool-carrying member in engagement with said lever, and means also supported by said housing for changing the position of said lever relatively to said tool-carrying member to vary the extent of movement of said member.

10 4. In a relieving mechanism, the combination with a movable tool-carrying member, a cam for imparting movement to said member, a shaft for driving said cam and on the end of which said cam is mounted, a lever arranged beyond said cam and having a lateral extension engaging said cam and a pivoted part, said lever being adapted to engage said tool-carrying member at a plurality of different portions of the lever, and means arranged beyond said lever and said cam for changing the position of said lever to vary the position of the lever with regard to said member to vary the extent of movement thereof.

25 5. In a relieving mechanism, the combination with a movable tool-carrying member, a cam for causing said member to move relatively to the work, a lever interposed between said cam and said tool-carrying member, means for adjusting the position of said lever relatively to said tool-carrying member to vary the extent of movement imparted to said member and a graduated scale with which said adjusting means co-35 operate for indicating the extent of movement imparted to said member.

6. In a relieving mechanism, the combination with a movable tool-carrying member, a cam for causing said member to move relatively to the work, a lever interposed between said cam and said tool-carrying member and having a part engaging said cam and a pivoted part, and means for moving said lever relatively to said 45 tool-carrying member and about the axis of said cam for varying the extent of movement of said member.

7. In a relieving mechanism, the combination with a movable tool-carrying member, a cam for causing said member to move relatively to the work, a lever interposed between said cam and said tool-carrying member and having a part engaging said cam, an adjustable member on which said lever is pivoted and which is provided with graduations for predetermining the relieving movement imparted to said tool-carrying member, and means for holding said adjustable member in various positions.

60 8. In a relieving mechanism, the combination with a movable tool-carrying member, a cam for causing said member to move relatively to the work, a lever interposed between said cam and said tool-carrying member and having a part engaging said cam, a

member adjustable substantially about the axis of said cam and on which said lever is pivoted, and means for holding said adjustable member in different positions to place said lever in different positions relatively to said tool-carrying member to vary the extent of movement thereof. 70

9. In a relieving mechanism, the combination with a movable tool-carrying member, a cam for causing said member to move relatively to the work, a lever interposed between said cam and said tool-carrying member and having a part engaging said cam and a curved part on which said tool-carrying member engages, and an adjustable member pivotally mounted in proximity to said cam and on which said lever is pivoted, said adjustable member being movable about its axis to place said curved part of said lever in different relations to said tool-carrying member to vary the extent of movement thereof. 85

10. In a relieving mechanism, the combination with a tool-carrying member, a rotary cam, a housing in which said cam is arranged, a lever engaging said cam and said tool-carrying member, and an adjustable member pivotally arranged in said housing and in which said lever is pivoted, said adjustable member being adapted to place said lever in different positions relatively to said tool-carrying member to vary the extent of movement thereof. 90

11. In a relieving mechanism, the combination with a tool-carrying member, a rotary cam, a housing in which said cam is arranged and a lever engaging said cam and said tool-carrying member, an adjustable member pivotally arranged in said housing and in which said lever is pivoted, said adjustable member being adapted to place said lever in different positions relatively to said tool-carrying member to vary the extent of movement thereof, and means for locking said adjustable member in the position in which it is set. 105

12. In a relieving mechanism, the combination with a tool-carrying member, a rotary cam, a lever engaging said cam and said tool-carrying member, means for yieldingly holding said lever in engagement with said cam, and means for adjusting said lever about the axis of said cam for varying the extent of movement of said tool-carrying member. 115

13. In a relieving mechanism, the combination with a tool-carrying member, a rotary cam, a driving shaft therefor on the end of which said cam is arranged, an adjustable member arranged beyond said cam, and a lever arranged between said cam and said adjustable member and having a part projecting from one side of said lever and engaging said cam and a pivot extending from the other side of said lever 125

and journaled in said adjustable member, said adjustable member being adapted to move said lever into various positions relatively to said tool-carrying member to vary 5 the extent of movement thereof.

14. In a relieving mechanism, the combination with a tool-carrying member, a rotary cam, a driving shaft therefor on the end of which said cam is arranged, an adjustable member arranged beyond said cam, and a lever having a body portion arranged between said cam and said adjustable member and having a part projecting from one side to engage said cam and a stud extending from the other side and pivoted on said adjustable member, said body portion being recessed and adapted to receive a part of said tool-carrying member, said adjustable member being adapted to move said lever 10 into various positions relatively to said tool-carrying member to vary the extent of movement thereof.

15. In a relieving mechanism, the combination with a movable tool-carrying member, a cam for imparting movement to said member, a housing for said cam, a shaft for driving said cam and which extends into one end of said housing, said cam being arranged on the end of said shaft, a lever arranged in said housing beyond said cam and having a part engaging said cam and a pivoted part, and means arranged in the other end of said housing and adjustable to change the position of said lever 20 relatively to said tool-carrying member to 30

vary the extent of movement of said member.

16. In a relieving mechanism, the combination with a tool-carrying member, a rotary cam, a lever engaging said cam and 40 said tool-carrying member, means for yieldingly holding said lever in engagement with said cam, and means for adjusting said lever to vary the extent of movement of said tool-carrying member, said lever being adapted 45 to be placed in a position in which no movement is imparted to said member.

17. In a relieving mechanism, the combination with a movable tool-carrying member, a cam for imparting movement to said member, a lever having a part engaging said cam and a pivoted part, said lever being adapted to engage said tool-carrying member at a plurality of different portions of the lever, and means for 50 changing the position of said lever to vary the position of the lever with regard to said member to vary the extent of movement thereof, said lever being adapted to be placed in a position in which the pivoted 55 part thereof is placed into operative relation to said tool-carrying member, whereby no movement is imparted to said tool-carrying member.

Witness my hand this 25th day of February, 1919.
